COMBINED TISSUE DISPENSER, AND LITTER AND ACCESSORY CONTAINER, FOR AUTOMOBILES

Warren Wilson, 4633 Roxbury Road,
Corona del Mar, Calif.

Filed Sept. 23, 1965, Ser. No. 87,124

Term of patent 14 years

(Cl. D58—12.6)

FIGURE 1 is a perspective view of a combined tissue dispenser, and litter and accessory container, for automobiles, embodying my new design, the cover being shown in open condition;

The side not shown in FIGURES 1 and 3 is identical to the side shown therein except that there is no horizontal slot, the surface instead being plain.

The dominant features of the design reside in the portions shown in full lines.

I claim:

The ornamental design for a combined tissue dispenser, and litter and accessory container, for automobiles, substantially as shown and described.
